(57) **CLAIM**

The ornamental design for a pedal power generating device, as shown and described.

DESCRIPTION

FIG. 1 is a perspective view of a pedal power generating device showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, showing the U-shaped handle in an alternate position; and,

FIG. 9 is a perspective view thereof, shown in environmental use.

The broken lines shown represent unclaimed subject matter and form no part of the claimed design.
